ATTORNEY.

UNITED STATES PATENT OFFICE.

CARL E. PETERSON, OF MONTCLAIR, NEW JERSEY.

SUSPENDER-SLIDE.

1,330,339.

Specification of Letters Patent. Patented Feb. 10, 1920.

Application filed May 29, 1919. Serial No. 300,603.

To all whom it may concern:

Be it known that I, CARL E. PETERSON, a citizen of the United States, and a resident of Montclair, county of Essex, and 5 State of New Jersey, have invented certain new and useful Improvements in Suspender-Slides, of which the following is a specification.

This invention relates to an improved suspender slide and is adapted for holding in 10 adjusted positions the strips or sheets of the suspender that go through the slide, and is particularly adapted for use with overalls and the like.

15 This slide is used in lieu of a buckle, and it has been the practice to make such slides of wire of various constructions, the majority of the constructions having a loose end of the wire, or having projecting uncovered 20 ends of the wire, which not only form means for cutting or tearing the fingers, but tend to become loosened.

25 My improved slide is formed in a manner to adapt it to tightly bind the strands of the suspender that pass through it against accidental movement, but permits a quick and positive adjustment of the slide when it is desired to lengthen or shorten the suspender.

30 The invention is further designed to provide a slide of this kind which will not catch on the suspender and which has its parts that project provided with rounded outside surfaces so that there is no obstruction that 35 is apt to be caught on anything, and the device being made of one piece of wire, both ends are turned inward and protected so that the shielded or covered ends of the wire offer no projection or obstruction.

40 The invention is illustrated in the accompanying drawing, in which Figure 1 is a top view of the improved slide. Fig. 2 is a face view with a strap of the suspender shown in dotted outline, broken away at the 45 top, and Fig. 3 is a central vertical section of Fig. 2.

45 I may use wire of different and various cross-sectional forms, but I prefer to use square wire, the wire being substantially 50 straight for a portion of its length to form a central strand 10, and being bent at the opposite ends of the central strand 10 in opposite directions to form the main end strands 11 and 12, these again being bent parallel 55 with the central strand 10 to form the top strand 13 and the bottom strand 14, these

being substantially parallel with the central strand and of approximately the same length.

The top and bottom strands 13 and 14 are 60 bent to form the supplemental end strands 15 and 16, respectively, these ending in their respective loops 17 and 18 which embrace the central strand 10 adjacent to its juncture with the main end strands 11 and 12. The 65 loops 17 and 18 are substantially parallel with the end strands of the slide and are carried around far enough so that the ends 19 are bent in close upon the wire itself so that its ends 19 are protected from engagement 70 with the clothing or fingers.

The slide is usually employed to hold the strips in adjusted relations, and in the form shown the suspender strip is fastened by the loop 20 to the central strand and then passes 75 down and is doubled on itself at 21, the part 21 being used to hold, in common practice, a catch to go over a button on the garment, although what is suspended from the loop 21 is immaterial. The suspender then passes, 80 as at 22, between the part 20 and the slide, then up around the outside of the loop 20, as at 23, and then behind the top strand, as at 24, and in this way is given enough sinuosity of form to enable it to be tightly held 85 by the slide when tension is applied on the two ends of the strap or suspender.

The square wire is preferable because it provides a better binding surface in its engagement with the fabric or material on 90 which the slide is used, although it will be understood that I do not wish to be limited to wire square in cross-section in manufacturing this slide.

The central strand 10 and the top and 95 bottom strands 13 and 14 can be in different relative planes, but I prefer to make them as shown in Fig. 3, in which the central strand 10 is slightly out of line with the top and bottom strands, thus providing more positive binding of the suspender strap, due to the increased bent or sinuous form into which it is forced when in the slide.

It will be evident from an inspection of the drawing that in general the formation 105 of the slide is that of a somewhat flattened S with the two ends twisted in engagement with the central strand. I prefer to pass the supplemental end strands 15 and 16 toward the same side of the central strand, in 110 the drawing they being shown inclined toward the rear so that the loops 17 and 18

are bent forward and thus pass around the central strand. The loops act to guide the suspender freely through the slide when the slide is to be moved, as the friction on the 5 sides when the strand is loosened will not retard the movement of the slide materially and it keeps the suspender and the slide in alinement.

I claim:

- 10 A slide comprising a single wire forming a central strand which extends at its ends in opposite directions to form main end strands, and then back in opposite directions to form

top and bottom strands, the wire extending from the top and bottom strands toward the 15 central strand to form supplemental end strands substantially in line with the main end strands, the ends of the supplemental end strands being slightly out of line with said ends and formed into coils embracing 20 said central strand and leaving no ends of the wire exposed.

In testimony that I claim the foregoing, I have hereto set my hand, this 28th day of May, 1919.

CARL E. PETERSON.
